UNITED STATES PATENT OFFICE.

FRANK A. THELEN, OF KEWANEE, ILLINOIS, ASSIGNOR TO ADOLPH MOHLER, OF KEWANEE, ILLINOIS.

MACHINE FOR CAPPING BOTTLES.

981,817.

Specification of Letters Patent. Patented Jan. 17, 1911.

Application filed June 10, 1909. Serial No. 501,304.

To all whom it may concern:

Be it known that I, FRANK A. THELEN, a citizen of the United States, residing at Kewanee, in the county of Henry and State 5 of Illinois, have invented a new and useful Machine for Capping Bottles, of which the following is a specification.

This invention relates to improvements in devices for applying caps or crowns to bottles and seeks to provide a device of simple 10 construction and operation which may be manipulated by unskilled labor to rapidly and efficiently apply crowns or caps to bottles.

15 The invention consists in certain novel features of the device shown in the accompanying drawings as will be hereinafter first fully described and then particularly pointed out in the claim.

20 In the drawings referred to, Figure 1 is an elevation of a bottle capping apparatus embodying my invention and indicating a bottle in position therein. Fig. 2 is an enlarged sectional view of the plunger. Fig. 25 3 is a detail perspective view of a gage employed to assist in properly positioning a bottle within the device. Fig. 4 is a detail sectional view of a part of the base and spacing blocks which may be placed thereon.

30 In carrying out my present invention I employ a base 1 which may be of any preferred form and of suitable dimensions to impart stability to the device and provide an ample support for the bottle. At the center of this base I place a mat 2 of rubber or other elastic material which receives the bottle and serves to cushion the same under the blow imparted thereto in applying the cap. Rising from the base are a pair of 35

pillars 3 which extend upward to support an arch or top 4 which is rigidly secured to the said pillars and is provided with a central opening in which is mounted a rod 5 having a plunger 6 secured to its lower end.

40 The upper end of this rod 5 is pivotally attached to an operating lever 7, the said lever being fulcrumed upon the arch 4 by means of a link 8 having its opposite ends pivoted, respectively, to the end of the lever and to 45 the upper side of the arch, as clearly shown in Fig. 1. These parts may be so relatively proportioned that the down stroke of the lever will impart just the proper movement

5 to the plunger head 6 necessary to firmly crimp the cap or crown over the mouth of the bottle.

The plunger head 6 comprises a casing 9 arranged between an upper plate 10 and a lower plate 11 which is secured by bolts 12 inserted through the said plates and provided with suitable securing nuts 13, as clearly shown in Fig. 2, the upper plate being secured directly on the end of the rod 5 and the lower plate being provided with a central opening 14 to admit the cap and the neck of the bottle. Within the casing 9 is placed a crimping block 15 having a central opening that is formed with two portions 16 and 17. The upper portion 16 of the crimping block is tapered upwardly and the lower 60 portion 17 is cylindrical, the said lower portion presenting a circular recess which will receive the cap and the upper tapered portion constituting a crimping chamber, the walls of which will engage the edge of the 65 cap so as to bend the same down over the neck of the bottle, as will be presently more 70 fully set forth.

Upon the base plate 11 of the plunger, and secured by and between the same and 75 the crimping block, is an annular resilient retainer 18 which is adapted to support the crown or cap until the same is crimped over the bottle neck. Within the tapered portion 80 16 of the crimping block is a spring 19 which is secured in the upper end of the plunger and serves to hold the cap against the mouth of the bottle as well as to cushion the impact of the plunger upon the 85 bottle.

90 In order to rapidly and accurately place the bottle at the center of the base plate 1, I provide the gage 20 consisting of a standard rising from the base plate, and diverging arms 21 at the upper end of the said 95 standard. The diverging arms present a recess to receive the bottle as will be readily understood on reference to Fig. 3, and at the junction of the said arms is provided a small body or plate 22 having a slot 23 through which the end of the standard projects, and on this projecting end of the 100 standard the thumb screw 24 is mounted and adapted to be turned home against the 105 said slotted body. This construction permits the arms to be adjusted forward or

backward upon the standard so that the device can be quickly adjusted to receive bottles of different diameters.

In order to accommodate bottles of different types, I employ the spacing blocks 25 which may be made of wood and are preferably circular and are provided on one side with a central lug 26 which may engage a recess 27 in the mat 2 or a small recess in 10 the upper side of the lower block when more than one block is employed. It will be understood that as many of these blocks may be utilized as may be necessary to raise the bottle to such a height that its neck will 15 project upward the proper distance to receive the crown or cap and have the same secured in position when the plunger is depressed.

It is thought the operation of the device 20 will be readily understood from the foregoing description, taken in connection with the accompanying drawings. The crown or cap in an uncrimped condition is pushed upward through the opening in the base plate 11 and the coincident opening in the retainer 18 so as to enter the recess 17 in 25 which it will be held by the projecting inner edge of the said retainer, it being understood that the retainer 18 will yield sufficiently to permit the entrance of the cap and will then at once spring into position below the same so as to prevent accidental dropping thereof. The operating lever is then 30 raised and the bottle placed in position upon the base plate of the machine or the spacing blocks 25, after which the lever is brought down so as to drive the plunger forcibly 35 over the neck of the bottle. The downward

movement of the plunger will carry the cap or crown directly onto the mouth of the 40 bottle, and as a result of the contact of these two parts, the cap will be carried upward into the tapered chamber 16, the walls of which will at once bend or crimp the edges of the cap firmly upon the mouth of the bottle 45 so that when the lever is again raised, the plunger will recede from the cap which will be retained on the mouth of the bottle, as will be readily understood. The cap thus applied to the bottle will be effectually secured thereto and cannot be removed therefrom except by the application of the usual implement employed for that purpose.

The device is composed of very few parts, 50 is easily operated, and is very efficient for 55 the purpose for which it is designed.

Having thus described my invention, what I claim is:

In a device for the purpose set forth, a plunger head comprising spaced plates connected together, one plate being provided with a central passage, a crimping block between the plates, a resilient retainer between the block and the plate provided with a central passage, the connecting means for the plates serving to clamp the block and the resilient retainer in place, and a spring lodged in the crimping block.

In testimony that I claim the foregoing as my own, I have hereto affixed my signature in the presence of two witnesses.

FRANK A. THELEN.
